UNITED STATES PATENT OFFICE.

LEWIS E. CURTIS, OF KENILWORTH, ILLINOIS, ASSIGNOR TO AMES STEEL LATH COMPANY, OF ST. LOUIS, MISSOURI, A CORPORATION OF MISSOURI.

METHOD OF MAKING EXPANDED METAL.

1,191,768.

Specification of Letters Patent. Patented July 18, 1916.

Application filed September 1, 1915. Serial No. 48,524.

To all whom it may concern:

Be it known that I, LEWIS E. CURTIS, a citizen of the United States, residing at Kenilworth, in the county of Cook and State of Illinois, have invented a certain new and useful Improvement in Methods of Making Expanded Metal, of which the following is a full, clear, concise, and exact description, reference being had to the accompanying drawings, forming a part of this specification.

This invention relates to improvement in methods of making expanded metal.

One object of the invention is to device a method or process of manufacturing expanded metal wherein the sheet is cut to form a strand, said strand being subsequently opened up simultaneously with the cutting of another strand, and so on across the full width of the sheet.

Another object of the invention is to provide a method or process of manufacturing expanded metal wherein the sheet is slit or cut to form a plurality of adjacent bonded strands with the slits and bonds staggered, the strands thus formed being subsequently opened up simultaneously with the slitting of an adjacent series of plurality of strands, these steps being duplicated across the width of the sheet.

The invention furthermore consists in the improvements in the steps and novel combination of the steps herein shown, described and claimed.

In the drawing forming a part of this specification, Figure 1 is a part side elevation part vertical section of one form of machine adapted to carry out my improved process. Fig. 2 is a transverse vertical sectional view of the machine shown in Fig. 1 and taken substantially on the line 2-2 thereof. Fig. 3 is a top plan of a portion of the machine, illustrating more particularly the arrangement of slitters and expanders. Fig. 4 is a view similar to Fig. 3, upon an enlarged scale, showing the first two sets of cutters and expanders. Fig. 5 is a sectional view of one of the sets of cutters and expanders taken substantially on a plane passing between the upper guiding disk 15 and stripper 30 shown in Fig. 2, and Fig. 6 is a detailed view of a portion of the sheet showing the same after it has passed the first set of cutters and second set of combined cutters and expanders.

In said drawing, 10 denotes the base casting or bed, the same having a longitudinally extending recess 11 in which are mounted a plurality of sets of expanders and cutters, hereinafter described, and the driving mechanism. Referring to Fig. 2, each set of cutters or slitters and expanders (with the exception of the first set, as more particularly pointed out hereinafter) comprises a cutting disk 12 secured to a vertically extending arbor 13, mounted in an adjustable bearing block 14; an upper cutting disk 15, which cooperates with the upper edge of the disk 12, a lower cutting disk 16, which cooperates with the lower edge of the disk 12, and expander 17. The disks 15 and 16 and the expander 17 are secured to an arbor 18 rotatably mounted in elongated bearing block 19, the latter being rigidly secured to the base casting 10 as by set screw 20. The bearing blocks 14 and 19 are hinged together as indicated at 21 whereby the former may be adjusted relatively to the latter as by the adjusting screw 22. The arbors 13 and 18, at their lower ends, are provided with meshing pinions 23 and 24 respectively. The arbor 18 is extended downwardly and on its lower end is provided with a worm gear 25 which meshes with worm 26 secured to the longitudinally extending driving shaft 27, said shaft 27 being driven from any suitable outside source of power through the pulley 28.

From the foregoing description, it will be seen that all the cutting disks and expanders are positively and uniformly driven and also that the cutters and expanders may be relatively adjusted. All the sets of cutters and expanders are as described in the foregoing with the exception of the first set. As shown in Figs. 3 and 4, the first set comprises merely cutting disks 112, 115 and 116 arranged similarly to and corresponding exactly with the other cutting disks 12, 15 and 16 respectively. No expander is employed with the first set of cutters or slitters for the reason hereinafter described. Associated with each set of cutting or slitting disks is a stripper secured to the corresponding bearing block 19. As shown, the stripper comprises a lower horizontal portion 29, an upright arm 30, and a horizontally extending finger or blade 31, which fits around the washer 32, which is employed to separate the cutting disks 15 and 16 and 115 and 116.

116. The fingers 31, as clearly appears in Fig. 5, are opposite their corresponding cutting disks 12 and 112. As clearly shown in Figs. 3 and 4, each expander 17 consists of an equilateral triangular shaped plate having the corners thereof rounded, as indicated at 33.

Extending lengthwise of the machine and so positioned as to properly present the sheet to be cut to the slitters and expanders, 10 is a guide-way 34 having a bottom 35 inclined upwardly from the entrance end of the machine toward the exit end. The inclination of the bottom of said guide-way 15 is in the ratio of the width of a strand to the distance between centers of bonds. In order to slit the sheet with interrupted slits parallel to the edges of the sheet, all the arbors 13 and 18, and consequently the disks 20 and expanders carried thereby, are inclined from the vertical, the inclination being such that the arbors 13 and 18 are perpendicular to the inclined bottom 35 of the guide-way. Furthermore, each cutting disk 15 is equal 25 in width to the width of two strands so that the corresponding expander 17 associated therewith will engage the proper strands and, as will be understood, all the cutting disks 15 and 16 and 115 and 116 are provided with equally spaced notches 34 around the periphery thereof, the notches of the disks 15 and 115 being properly staggered or alternated with the notches of the disks 16 and 116 respectively, to thereby slit the 30 sheet with bonded strands wherein the bonds are staggered in the usual manner.

The operation is as follows: As the sheet "S" passes the first set of cutting disks 112, 115 and 116, it will be slit so as to form 40 two strands "a" and "b" with the bonds staggered. As the sheet advances to the next set of slitters and expander associated therewith, two more strands are formed as indicated at "c" and "d", the strands "c" 45 and "d" being adjacent and similar to the strands "a" and "b", as will be understood. Simultaneously with the slitting of the sheet "S" to form the strands "c" and "d", the expander 17 which is associated with the cutting disks that form the strands "c" and "d", will engage the previously formed but unopened strand "a" and will open the latter directly to thereby form a mesh, as clearly indicated in Fig. 6. As the expander 50 17 directly opens up the strand "a", the second or adjacent strand "b" will be indirectly opened up thereby, as indicated in Fig. 6. Similarly, as the sheet advances to the next set of slitters and expanders, another 55 pair of strands will be formed, and simultaneously with the formation thereof, the expander associated with said set of slitters will directly open up the strand "c" and indirectly the strand "d". This series of steps 60 is continued across the full width of the

sheet "S", thereby expanding the entire sheet, and in a plane substantially perpendicular to the normal plane of the sheet.

From the preceding it will be seen that when the front edge of the sheet has reached 70 the last set of cutters and expanders, then thereafter the sheet is slit with successive, diagonally arranged series of slits in stepped pairs, the strands of one pair formed by the slitters being opened up subsequently by the expander associated with 75 the next adjacent set of slitters.

I have herein described specifically one method of carrying out my improved process, but the same is merely descriptive and 80 I do not wish to be limited thereto but contemplate such changes and modifications of the steps and combination of the steps of the process as come within the scope of the 85 claims appended hereto.

I claim:

1. The herein described method of manufacturing expanded metal which includes, 90 slitting without expanding a portion of a sheet to form bonded strands, successively opening up the strands thus formed simultaneously with the slitting without expanding of an adjacent portion of the sheet to form bonded strands, and so on across the width of the sheet.

2. The herein described method of manufacturing expanded metal which includes, 95 slitting without expanding a sheet to form a strand bonded at intervals to the body of the sheet, subsequently opening up said strand thus formed simultaneously with the slitting without expanding of the sheet to form another similar strand in proximity thereto, and repeating the foregoing sequence of steps across the width of the sheet.

3. The herein described method of manufacturing expanded metal which includes, 100 slitting without expanding a portion of sheet to form a plurality of parallel bonded strands, then slitting another adjacent portion of the sheet to form another plurality of bonded strands, the strands first formed being simultaneously opened with the slitting of the sheet to form the second set of strands.

4. The herein described method of manufacturing expanded metal which includes, 105 slitting a portion of a sheet, then slitting an adjacent portion of the sheet, and simultaneously with the latter operation, opening up the first slit portion, the simultaneous slitting and opening taking place substantially in the same line transversely of the sheet.

5. The herein described method of manufacturing expanded metal which includes, 110 slitting the sheet to form a pair of parallel bonded strands, then slitting the sheet to form another pair of parallel bonded strands, and simultaneously with the latter 115

120

125

130

operation, opening up one of the previously formed strands directly and the other of the previously formed strands indirectly.

6. The herein described method of manufacturing expanded metal which includes, slitting a sheet with successive diagonally arranged series of cuts in stepped pairs of cuts, and opening up the strands formed by one pair of cuts simultaneously with the cutting of the adjacent pair of cuts.

7. The herein described method of manufacturing expanded metal which includes, slitting a sheet to form adjacent bonded strands "a" and "b", then slitting the adjacent portion of the sheet to form bonded strands "c" and "d", and simultaneously with the slitting operation which forms the strands "c" and "d", opening up the strands

"a" and "b" at points immediately adjacent thereto.

8. The herein described method of manufacturing expanded metal which includes, slitting a sheet to form adjacent bonded strands "a" and "b", then slitting the adjacent portion of the sheet to form bonded strands "c" and "d", and simultaneously with the slitting operation which forms the strands "c" and "d", opening up the strands "a" and "b", the strand "a" being opened directly and the strand "b" indirectly.

In witness that I claim the foregoing I have hereunto subscribed my name this

24th day of Aug. 1915.

LEWIS E. CURTIS.
